SPOOL BOX

Walter H. Collins, Summit, N. J.

Application January 15, 1953, Serial No. 23,145

Term of patent 7 years

(Cl. D3—19)

To all whom it may concern:

Be it known that I, Walter H. Collins, a citizen of the United States of America, residing at Summit, in the county of Union and State of New Jersey, have invented a new, original, and ornamental Design for a Spool Box, of which the following is a specification, reference being had to the accompanying drawing forming part thereof.

Fig. 1 is a perspective view of a spool box embodying my new design;

Fig. 2 is a cross sectional view of the same on a larger scale; and

Fig. 3 is a top plan view thereof.

I claim:

The ornamental design for a spool box, substantially as shown.

WALTER H. COLLINS.
